Application August 5, 1935, Serial No. 34,682

26 Claims. (Cl. 200—152)

Our invention is concerned primarily with switches of the mercury contactor type, and particularly with switches having a metallic switch envelope in place of the glass type envelope formerly employed, which has sealed-in metallic electrodes, although certain features of the present invention are applicable to such glass envelope switches.

The specific embodiments herein disclosed are 10 heavy duty switches suitable for a heavy schedule of switching of power current. While our invention is especially useful for heavy duty switches, certain phases of the invention are equally applicable to light duty or small capacity switches.

15 In mercury switches of the glass envelope type, the envelope is either evacuated or provided with a filling of hydrogen, neon, or a similar gas, usually under pressure. There are distinct disadvantages in both types of glass envelope switches, since the inability to dissipate heat results in excessive temperature of the inleads with resultant leakage about the seal. Such leakage admits oxygen to the interior of the envelope, resulting in rapid deterioration of the switch, or 25 explosion of the hydrogen filling.

The chief disadvantage of glass envelope switches of the mercury type is that there is a considerable difference in the coefficients of thermal expansion of the glass and of the metallic electrodes. This results in a definite limitation of the size of the electrode that can be employed, directly limiting the current carrying capacity of the switch, since heating of the electrode produces severe strains in the glass surrounding its point of entrance into the switch, and in most cases results in loosening of the seal or cracking of the envelope, both of which results are disastrous to the life of the switch.

This has induced a tendency to use metallic 40 shell type mercury switches, but such constructions present other disadvantages limiting their use. With a metallic envelope type of switch, there is difficulty in keeping the parts free of impurities, and surface oxidation particularly, during the assembling process. Impurities tend to foul the mercury as well as the contact surfaces, and tend to increase the contact resistance. Also, where a thin metal section is employed, the thermal capacity is low and the rate 45 of heat transmission is limited thereby. In such constructions the heat generated by a rapid succession of making and breaking of relatively high currents cannot be readily dissipated, causing uneven heating up of the parts and tending to 50 break the seals about the electrodes. This tends 55

to permit infiltration of air, causing oxidation of the inner surfaces of the shells.

Attempts have been made to fill such switches with hydrogen gas, but hydrogen gas is very difficult to retain. Hydrogen will leak through pores 5 that will not pass other gases. It has also been attempted to employ liquid fills in such switches, but thus far no commercially practicable liquid fill switches have appeared on the market or been available. We have found that liquid filled 10 switches prior to our present invention would almost invariably explode upon continued interrupting operation at their rating, or upon over-load.

Our present invention contemplates a mercury 15 switch of the sealed envelope type, in which the interior of the switch envelope is cleaned thoroughly prior to assembly, and kept clean during operation. In the preferred form of our invention we employ a cup-shaped metallic shell 20 which has a ceramic insert sealed in one end thereof and having an electrode carried thereby, the shell itself serving as the second electrode.

In order to reduce the localization of heat generated by the arcing produced during opening 25 and closing of the switch as much as possible, we provide a switch construction in which this generation of heat takes place away from the metallic switch parts. This greatly reduces the tendency for pitting and oxidation of the metal. This construction also secures the beneficial action of 30 a mercury to mercury making and breaking of the contact. Also, our present construction removes this generation of heat as far as possible from the point of sealing of the ceramic insert 35 into the open end of the shell, serving to protect this seal from the heat.

One of the primary objects of our present invention is the use of a liquid fill which is limited 40 in volume with respect to the vapor space in the switch envelope. This limited liquid fill to vapor relation is of distinct advantage in connection with several phases of this type of switch construction. In the first place, the liquid fill which we preferably employ is a slightly viscous 45 liquid having a relatively high boiling point. The preferred liquid is triethanolamine. We may utilize a mixture of castor oil and alcohol. We do not wish to be limited to the above named liquids as others may be employed but the foregoing 50 appear to be suitable for this purpose.

Only a limited quantity of such liquid is employed, the major portion of the interior of the switch envelope being employed as a vapor chamber. Upon slight heating of the liquid fill by 55

the making and breaking of contact within the switch, the liquid starts to boil, and the vapor chamber becomes filled with vapor which condenses on the defining surfaces of the envelope 5 and runs back as a liquid into the main body of liquid.

The use of a limited amount of liquid fill with respect to the volume of the chamber produces the beneficial action, that the liquid fill upon boiling 10 and subsequent condensation acts as a highly effective medium for dissipating heat generated at a localized point in the switch uniformly to all parts of the envelope, whereby the heat is rapidly conducted away from the arcing point and 15 dissipated throughout the switch. This prevents the temperature at the heat generating point from rising above the boiling point so long as there is liquid in contact with the heated part.

Another beneficial action secured by the use of 20 a relatively large vapor space in the envelope compared to the amount of liquid fill employed resides in the limitation of the vapor pressure which can be generated by converting all of it to a vapor.

25 Still another beneficial action secured by this limitation of the liquid fill resides in the reduction of resistance to movement of mercury contactor, since it does not have to displace any appreciable quantity of liquid during its movement into and 30 out of contacting engagement. The use of a liquid fill of this type is also advantageous in that as the pressure builds up inside the envelope, due to the heat of the arc, the arc value is thereby reduced by the increased pressure, preventing the 35 formation of any appreciable arcs during rapid operation of the switch.

The particular characteristics and advantages of liquid fills as to their action on the metallic surfaces and the like are fully disclosed in our 40 copending application, Serial No. 745,842, filed September 28, 1934.

Another feature of the present invention is the simplified, compact and efficient switch structure which we employ in connection with the concept 45 of limiting the liquid fill to vapor relation. The structure which we herein disclose is designed to utilize the advantages of the limited liquid fill but obviously many, if not all, of the advantages may be realized in other structures or types of structures, though generally less in degree.

50 Other objects and advantages of the present invention will appear more fully from the following detailed description, which, taken in connection with the accompanying drawings, will disclose to those skilled in the art the particular construction and operation of a preferred embodiment of our present invention.

In the drawings:

55 Figure 1 is a vertical sectional view through one form of switch embodying the principles of the present invention, the switch here shown being a low angle switch;

Figure 2 is a view similar to Figure 1, through a modified type of switch, this switch being a high angle switch;

Figure 3 shows the switch of Figure 2 in the other of its operating positions;

Figure 4 is a sectional view taken substantially on line 4-4 of Figure 2, showing the internal 70 construction of the switch;

Figure 5 is a detailed view of a modified type of insulating sleeve embodied in the switch shown in Figure 2;

75 Figures 6 and 7 are corresponding views of still further modified types of insulating sleeve;

Figure 8 is a sectional view through a modified type of metal shell switch;

Figures 9 and 10 are similar views through ceramic shell type switches; and

Figure 11 is a fragmentary section through a modified form of electrode and stud.

Referring now in detail to the drawings, in Figure 1 we have provided a substantially cup-shaped metallic shell 10, having an outwardly flared open end portion 12 adapted to receive the 10 ceramic insert 13, preferably porcelain of the wet process type, which insert is provided with an outwardly flaring tapered spillway or runway 14 extending into the shell 10 toward the closed end thereof. The shell 10 is preferably a drawn sheet 15 metal member formed of iron or stainless steel or alloy of iron.

The insert 13 is provided with an annular disc or ring member 15 of iron, stainless steel or alloy of iron forming an electrode, which member is 20 provided with a threaded stud 16, also of iron, stainless steel or alloy of iron, extending outwardly through a tapered opening formed substantially coaxially of the spillway 14 and extending outwardly of the ceramic insert 13. The stud 25 16 is secured in position to hold the electrode 15 in proper position by means of a washer member 17 and nut 18 threaded thereon and bearing against a suitable resilient conical gasket or packing member 19, which is compressed axially in 30 order to expand it radially. This gasket or packing member 19 preferably is formed of natural or artificial rubber or like impervious expandable material, or any other suitable material. A suitable recess permitting lateral expansion at the 35 outer end of the conical packing member 19 may be provided for keeping the rubber under compression without completely filling the available space. This allows the washer 47 to rest against the ceramic 13. Alternately, the washer 47 may 40 rest solely upon the end of the rubber gasket 49. A conductor 20 is soldered or otherwise suitably secured to the outwardly extending end of the stud 16.

The electrode 15 is disposed within a substantially cylindrical recess 22 formed at the rear end of the outwardly flaring spillway 14, the recess 22 providing a retaining ring or groove adapted to carry a small body of mercury 23 therein which is in engagement with the electrode 15, and which is adapted to have contacting engagement with a second body of mercury 24 upon tilting of the switch to move the body of mercury 24 up the inclined spillway 14 into contact with the body of mercury 23.

55 The junction of the spillway 14 with the recess 22 provides a shoulder, the edge of which is sharp and includes a solid angle of less than 90° whereby accurate repeat performance is secured.

In assembling the component parts of the 60 switch, the insert 13 is secured in the flared end 12 of the shell 10 by means of a sealing gasket 25, which may be formed of natural or synthetic rubber or other suitable material, and which is compressed partly axially and partly radially and 65 laterally of the tapered surfaces 26 and 27 of the insert when the insert is moved into position within the end of the shell 10. A suitable metallic retaining ring 27' of frusto-conical section is carried by the outer end of the insert, and the 70 outwardly defining edge of the flared portion 12 of the shell 10 is spun inwardly over the longitudinally extending end of the gasket 25 and ring 27', as shown at 28, to compress and displace the gasket into final position to seal the 75

insert within the shell. The spun-over edge 28 serves to prevent displacement of the insert 13 outwardly of the shell 10 by internal pressure. A slight expansion space for the end of the rubber gasket 25 should be allowed near or at ring 27.

The shell 10 forms the second electrode for the switch, having secured thereto a conductor 29 which may be soldered or otherwise suitably secured to the external surface of the shell 10, as indicated at 30.

In the assembly of the switch structure shown in Figure 1, the closed and rounded end 32 of the shell 10 is provided with a threaded inwardly extending portion receiving the closing screw 15 or sealing plug 33. When the insert, with its electrode fixed in position, is sealed within the open end of the shell, the shell is tipped upwardly with the end 32 thereof disposed at the top of the switch, and the mercury 23 and 24, of a predetermined amount, is placed in the switch envelope through the opening closed by the plug 33. A suitable quantity of liquid fill, indicated at 20 35, is then forced into the interior of the shell 10, the interior of the shell being first evacuated to 25 produce a relatively high vacuum therein, and being washed in any suitable manner to drive out any occluded gases or the like. Before the liquid fill has been introduced, and with a vacuum in the chamber, the chamber may be filled, 30 preferably under a slight pressure, with any suitable gas which is substantially inert or non-corrosive with respect to the metal and with respect to the liquid fill. This may be neon, argon, nitrogen, carbon monoxide, hydrogen helium, or 35 the like. The amount of liquid fill 35 which is inserted is predetermined with respect to the volume of the interior of the switch envelope. In a preferred embodiment of the invention the quantity of liquid fill for a switch envelope having approximately a 21 cc. volume comprising 40 about 0.5 cc. of liquid fill, which, together with the mercury and the like, provides for approximately 13.5 cc. of vapor space within the chamber. In a preferred embodiment of our switch, 45 the internal volume of the switch chamber is 21 cc. and approximately 7 cc. of mercury is employed as a contactor. The liquid fill may run anywhere from $\frac{1}{2}$ cc. to 1 cc., leaving a vapor space of approximately 64% of the total volume of the 50 switch chamber. We have shown the liquid as exaggerated in amount in the drawings, for the sake of illustration. In practice, the liquid has a tendency to spread and wet all of the inside surface of the container. The liquid film is shown 55 as of an exaggerated thickness, for purposes of illustration.

When the connection to the opening into which the closure plug 33 extends is removed, a portion of this gas escapes, providing a vapor space 60 above the liquid fill 35. The closure plug 33 is then immediately screwed into place and the entire external surface of the switch envelope and the ceramic insert may be coated with a coating of "Bakelite", cellulose acetate, or the like.

65 It will be noted, in this embodiment of the invention, that the making and breaking of contact occurs at the acute angle formed between the sloping spillway 14 and the side wall defining the cylindrical recess 22. Thus, the heat generated 70 is generated at a point removed from the metal itself, and inasmuch as the liquid fill surrounds, or at least wets, this particular point of making and breaking of contact, the liquid fill is heated to an extent such that a portion of 75 it vaporizes. This vapor then comes into contact

with the relatively cool walls throughout the remainder of the switch envelope, is condensed, and runs back down the side wall of the envelope into the main body of liquid fill. This ebullition of the liquid fill and the subsequent condensation of the vapor, due to the use of a definitely limited quantity of fill, prevents any excessively high rupturing pressures within the envelope, even if all of the liquid vaporizes.

We preferably employ triethanolamine as the 10 liquid fill, this liquid having a relatively high boiling point and having the characteristic of maintaining the switch surfaces clean and free from foreign materials. If desired, however, a mixture of castor oil and alcohol may be employed, the castor oil being employed in the form 15 commercially known as "Ricinine". Any liquid of this class which is anhydrous, alkaline in reaction, possesses arc extinguishing characteristics and has about the same viscosity and boiling point, may be employed.

It will also be apparent that the generation of heat at this acute breaking angle will be transmitted directly to the liquid fill, and by reason of the vaporization of this liquid fill will be dissipated substantially uniformly throughout the entire switch envelope, whereby the entire surface of the metallic shell 10 can be used for heat conduction away from the point of generation of heat, whereby the heat will be rapidly dissipated 20 to the surrounding atmosphere. Thus the limited liquid fill performs three important functions 25 in a switch of this type, namely, a maintenance of a relatively low pressure, less than the rupturing or leakage pressure caused by its ebullition due 30 to the heat generated by arcing of the mercury to mercury contact; secondly, its use as a heat transferring medium for dissipating the localized heat generated by the arc within the switch to all 35 points of the switch envelope; and thirdly, the 40 reduction of the arcing time due to the increased pressure within the switch envelope caused by evaporation of the fill, whereby upon increased rapidity of operation the pressure increases and the arcing time, or the length of the arc, decreases. By maintaining the volume of liquid fill 45 employed relatively small with respect to the volume of the vapor space indicated at 36, it occupying only about 3% of this volume, it is apparent that high internal pressures within the switch 50 envelope will not be developed even though all, or substantially all, of the liquid fill be vaporized. Thus by the limited liquid fill both hot spots 55 which are particularly destructive of glass envelope switches and high pressures which are destructive of all forms of switches are avoided or greatly reduced.

It is to be observed that our system of internal circulation of the liquid fill is unique. The liquid forms a viscous film in contact with the internal 60 surfaces and particularly with the mercury, which is always subject to heat generation by both the flow of current through it and by the arc produced at either making or breaking of the circuit.

This film of liquid is vaporized locally, i. e., at 65 the point where heat is generated. The vapor tends to fill the entire vapor space and selectively flows to the coldest region because it is there most rapidly condensed. By the employment of a liquid 70 the boiling point of which is at a substantially higher temperature than that of the surrounding air, i. e., by providing a substantial temperature differential, the heat of vaporization which is given off by the vapor in condensing on the inside surfaces is readily dissipated.

The condensed liquid, being viscous, runs back slowly, and thereby tends to give off heat in excess of the heat of vaporization, i. e., a substantial part of the heat of the liquid. Thus the viscosity tends to regulate the rate of circulation of the liquid back to the point of heat generation by gravity. The liquid of the thin layer or film is thus elevated by heat, i. e., vaporization, and delivered to the point where it liquefies and returns by gravity. Thus there is an internal circulation of the liquid in the switch. This action is highly advantageous, and is particularly useful in heavy duty metal shell switches.

There is a peculiarly useful feature in the constitution of the liquid fill as above disclosed. The high boiling point, viscosity, and the limitation of amount provide an ideal coordination of features, for not only is the heat easily dissipated, but the rise of pressure is also limited.

In the construction of the porcelain insulator 13 it is advisable to construct the same of two parts joined together because of the difficulty otherwise encountered in producing the sharp annular shoulder and the annular recess 22. The joint between the two parts is made preferably at a point along the length of the recess 22 where the gasket or seal 25 will prevent any possible leakage of the joint from communicating with the outside. Thus an imperfect joint between the two porcelain parts does not destroy the usefulness of the switch. The parts may be produced and fired and then cemented together or they may be joined before firing if desired.

The electrode 15 it will be observed is adapted to engage the mercury both on its axially facing or end surface and on its radially facing or side surface. This radial bearing or contact reduces the contact resistance between the electrode and the mercury with minimum amount of mercury in the recess 22 while preserving the desired repeat performance.

Considering now Figures 2 to 4, inclusive, the switch shown in this embodiment of the invention comprises a drawn metallic shell 40 of iron, stainless steel or suitable iron alloy, having the flared end 42 adapted to receive a ceramic insert 43 of porcelain or the like, the insert 43 having a forwardly extending substantially cylindrical sleeve portion 44, which sleeve portion is adapted to receive a tubular sleeve electrode 45 which may be of drawn sheet metal of the same material as the shell 40 and which electrode is carried by the headed end of a shank 46 extending outwardly through the rear end of the insert 43. The sleeve 45 and the shank 46 are secured in fixed position with respect to the insert 43 by means of the washer 47 and nut 48 threading over the extending end of the stud 46, there being a suitable resilient conical rubber bushing or gasket 49 interposed about the stud and compressed and expanded within the defining wedge-shaped opening in the insert through which the stud extends by endwise pressure of washer 47. A suitable electrical conductor 50 is soldered or otherwise secured to the outwardly extending end of the stud 46. The sleeve 45 may be made of iron or stainless steel or the like with a copper stud 46 brazed to the end wall thereof, as shown as a modification in Figure 11.

It will be noted that the outer end of the tubular sleeve electrode 45, indicated at 52, is disposed inwardly of the end of the ceramic sleeve 44, and that a body of mercury 53 forming part of the mercury fill is carried within this sleeve in engagement with the inner surface of the sleeve

and the head end of the stud 46. A second body of mercury 54 forming the rest of the liquid fill is carried within the shell 40 about the outer surface of the ceramic sleeve 44, the two bodies of mercury being adapted to have contacting engagement beyond the outer end of the ceramic sleeve 44 when the switch is tilted about its longitudinal axis. The insert 43 is secured within the open end of the shell 42 in the same manner as described in connection with Figure 1, there being a suitable resilient gasket 55 and clamping ring 55' interposed therebetween, the outer edge 56 of the shell being spun over the rear portion of the gasket and about the outer surface of the ring to retain the insert in cushioned sealed engagement within the end of the shell 40 substantially. A second conductor 57 is secured at 58 to the external surface of the shell 40, whereby control of the circuit through the conductors 50 and 57 is provided by movement of the bodies of mercury 53 and 54 within the switch. The closure plug 59 corresponds to the closure plug 33 of Figure 1, and is employed in the same manner.

A suitable liquid fill 60 is introduced into the interior of the switch envelope, and is so proportioned with respect to the vapor space 62 that free ebullition of the fill is provided for washing the internal surfaces of the shell 40, the sleeve 44 and the tubular electrode 45, as well as the mercury itself. This vapor space 62 also provides for free transmission of the heat generated at the outer end of the sleeve 44 due to making and breaking of contact thereover between the bodies of mercury 53 and 54, to all parts of the switch envelope, whereby no localized points of heat generation are allowed to build up.

In the operation of the switch shown in Figures 2 and 3, when the switch is in the position shown in Figure 2 the circuit is broken between the bodies of mercury 53 and 54, which are in respective engagement with the electrodes 45 and 40. Upon tilting of the switch in a counterclockwise direction about its longitudinal axis, as shown in Figure 3, the two bodies of mercury 53 and 54 both move forwardly with respect to the end of the sleeve 44, and come into engagement about the defining edge of this sleeve, thereby closing contact between the electrodes 45 and 40. It will be noted that the point at which contact is made and broken is about the defining edge of the ceramic sleeve 44, spaced away from the ceramic 43 and from the inner surface of the shell 40. This provides for generation of heat at a point removed from the electrode seal 49, and from the ceramic seal 55.

In addition, it removes the point of generation of heat away from any of the metal surfaces of the electrode 45 or electrode 40, and consequently provides for free action of the liquid fill 60 in dissipating this heat to all parts of the switch envelope, and preventing building up of localized heated spots. Also, due to the definite relation of the sleeve 44 with respect to the shell 40, a positive opening and closing of contact at the same points of inclination is assured, thus giving "repeat" performance, that is, the opening and closing of the switch at the same angular positions for successive operations of the switch.

Referring now to Figure 5, we provide a ceramic sleeve 44', which may correspond to the ceramic sleeve 44 of Figures 2 to 4, inclusive, but which is not as great in longitudinal extent. To the extending end of the sleeve 44', which is provided with the annular shoulder 65, we secure a modified type of breaking edge, which is shown as a 75

substantially cylindrical sleeve 66 having an inwardly extending tapered portion 67 at the outer end thereof, the sleeve 66 being provided with extending cylindrical flange portion 68 extending about the shoulder 65, the sleeve 66 being secured to the sleeve 44' by cementing. The breaking edge formed by the tapered surface 67 is considerably wider in extent, that is, is radially thickened to provide for slow motion operation of the switch, whereby the two bodies of mercury 53 and 54 will not come together with as great a rapidity as provided merely by the sleeve 44. Optionally this edge may be cut back, as shown in Figure 7, to increase the acuteness of the breaking angle.

In Figure 6 we show a still further modified form of breaking edge, comprising a sleeve member 70, having a suitable recess portion 72 for receiving the end of the stub porcelain sleeve 20 44', and having a double rounded outwardly extending defining edge 73, which provides a spill-over or snap operation of the switch, due to the fact that the two bodies of mercury snap over the rounded portion of the edge 73 and come into engagement in a direction substantially normal to their original direction of movement. This provides for engagement of the mercury at an accelerated speed of engagement, which produces a sufficient impact to completely close 30 the circuit without any frying or sputtering between the advancing edges of mercury as the switch should be slowly tilted. It is to be observed that in the forms shown in Figures 2 to 7, both bodies of mercury have movement toward 35 and away from each other, with the resultant double speed of engagement and separation.

In the embodiment of the invention shown in Figure 7, we provide a still further modified type of breaking edge comprising the sleeve 75 having 40 the cutaway annular ring portion 76 for cementing the same to the end of the stub shaft 44', and provided with an externally chamfered acute angle breaking edge 77, cut back from the inner defining periphery of the sleeve 75. This edge 45 forms a definite and positive point of separating the mercury, whether moved rapidly or relatively slowly, and thereby permits repeat performance, i. e., the feature of making and breaking contact at the same angle at all times. This 50 feature we believe to be unique in this sleeve type of switch. The present switch requires to be held in no particular angular position about its axis, since it is symmetrical with respect to its longitudinal axis.

In Figure 8 we have provided a switch requiring only a small operating angle. In this construction the metal shell 80 is provided with the usual 55 filler opening 82 and sealing plug 83. At its open end the shell 80 receives the ceramic insert 84 cushioned in sealed engagement within the shell by means of the annular tapered compressible gasket 85 and the frusto-conical ring 86 which is pressed longitudinally against the gasket by the spun-over edge 87 of the shell 80.

Extending centrally through the insert 84 is a second electrode stud 88, having an inner hemispherical head portion 89, preferably formed of a non-wetting metal, such as stainless steel, projecting outwardly of a central boss 90 formed on 70 the insert. The surface of the insert adjacent the boss 90 is annularly recessed, as at 92, to position the head 89 of the second electrode inwardly of adjacent portions of the insert. The stud 88 is secured in position by a washer 93 and nut 75 94 engaging the outer end thereof, the insert be-

ing provided with an outwardly flaring recess 95 receiving the compressible sealing gasket 96 for sealing the shank of the electrode with respect to the insert. As here shown, the washer 93 rests against the end of gasket 95 only.

A predetermined body of mercury 97 is disposed on the floor of the switch envelope, and it will be noted that the lower surface of the electrode head 89 is positioned substantially at the lower edge of the head approximately .015" 10 lower than the meniscus height of the mercury 97, whereby the mercury will make contact between the shell 80 and the electrode 89 without first engaging the ceramic 84. The floor of the envelope is thus maintained level and no uphill 15 rolling of the mercury is necessary. The included angle of operation of such a switch can be maintained within $\frac{1}{2}^{\circ}$. The interior of the envelope is provided with a partial filling of triethanolamine, or a similar liquid having equivalent properties, as indicated at 98, in the manner described in connection with previous embodiments of the invention.

Figures 9 and 10 are directed to a switch of the ceramic shell type, and disclose switches of 25 the same general construction as indicated by corresponding reference numerals. Thus we provide a ceramic cup-shaped shell 100 having an annular externally thickened portion 102 adjacent its open end. The closed end of the shell 30 100 is adapted to receive an electrode button 103 having a shank portion 104 extending through the shell and sealed with respect to the shell by the tapered gasket 105 which is axially compressed into sealing position by the nut 106 engaging the outer end of the shank 104.

At its opposite end, the shell 100 receives the closure cap 107 having the annular clamping portion 108 provided with a spun-over edge 109 engaging the frusto-conical washer 110 for compressing the resilient gasket 112 into tight sealing engagement with the external tapered surfaces of the portion 102 of the shell. Welded, or otherwise suitably secured to the inner surface of the cap member 107, is a tubular sleeve member 113 having a relatively snug fit in the interior of the shell 100 and being closed at its opposite end across the inner face of the cap member 107. A suitable filler opening is formed in the members 107 and 113, and is closed by the filler plug 114.

Referring now specifically to Figure 9, a body of mercury 115 is disposed within the envelope comprising shell 100 and sleeve 113, and upon tilting of the envelope the mercury is adapted to move toward and away from the electrode button 103, which is preferably formed of stainless steel or other metal not wet by the mercury. This produces contact between the sleeve 113 and button 103, and controls the circuit through the two flexible leads 116 and 117 electrically connected to the button and the sleeve. Suitable liquid fill is introduced into the envelope, as indicated at 118, to take care of heat dissipation and the like.

In Figure 10 we have modified the construction to produce a switch having a larger operating angle and having mercury-to-mercury making and breaking contact. The button 103 of this embodiment is provided with a substantially 70 hemispherical cup member 120 held in the closed end of the shell 100 by the electrode 103. An annular insulating ring 122, having an internal frusto-conical spillway surface 123, is inserted into position with the small end of the spillway 75

adjacent the cup 120, whereby a small body of mercury 124 is trapped on the inner surface of the cup behind the vertical edge 125 of the ring 122. The ring 122 is cemented or otherwise 5 suitably secured in position.

The sleeve 113 and cap member 107 are assembled in position in the manner previously described, and the body of mercury 115 is introduced into the switch envelope. In the operation 10 of the switch to close the circuit, the mercury 115 moves to the left, up the surface 123, and then, due to its accelerated movement up the converging surface, rushes into contact with the mercury 124, closing the circuit through the 15 switch. Upon opposite tilting of the switch, the mercury moves down the diverging surface with increased momentum, until finally the gravitational pull overcomes the cohesion between the bodies 124 and 115, and the mercury is parted 20 over the sharp edge between surfaces 123 and 125, whereby the surface tension snaps the adjacent contiguous edges into reeded position. Thus a substantially snap action type of switch is produced.

25 It will be noted that in both Figures 9 and 10 the actual making and breaking of the circuit occurs at a point removed from the gaskets 112, whereby the gaskets are disposed at the relatively cool portion of the switch.

30 It is of paramount importance that the relation of the volume of liquid fill to the volume of the vapor chamber be accurately controlled in order that proper limitation of pressure during heating be obtained. The liquid film provides 35 for cleansing of the internal surfaces of the switch envelope and keeping them clean. The vapor produced by boiling, and its condensation, provides for rapid dissipation of heat from a localized point of heat generation in order that overheating of any particular portion of the 40 switch will be prevented. It is apparent, however, that this ratio or relationship between these two factors may be varied, depending upon the type of switch which is employed, the current which it is required to control, and other similar 45 factors which must be considered. Therefore, while we have disclosed a particular ratio of approximately 3% of liquid fill in the vapor space, we do not intend to limit the invention to exactly this particular percentage, since it is obvious 50 that the proportions can be regulated or varied as desired to meet certain specified conditions.

One primary concept involved in this phase of 55 the present disclosure is to reduce the amount of liquid fill to the point that when the entire liquid fill is vaporized the pressure of the vapor will then not exceed the strength of the shell or container of the switch. This medium, i. e., a condensing vapor, is a highly efficient means for 60 transferring heat. The parts are so proportioned that on rated maximum duty the liquid will not all be vaporized, but sufficient vaporization occurs to carry off the necessary amount of heat 65 to keep the temperature within safe limits. If rated maximum is exceeded the pressure may rise, but never to the point of breaking or destroying the container.

We do not intend to be limited to the specific 70 details shown and described, nor to the proportions or sizes shown, as modifications of our invention will be obvious to those skilled in the art.

We claim:

1. In combination, in a switch of the class described, a cup-shaped metal shell having an en-

larged open end, a ceramic insert in the open end of said shell, resilient sealing means compressed radially between said insert and the interior of said enlarged opened end, a ceramic sleeve extending longitudinally inwardly from 5 said insert and of a diameter substantially less than the internal diameter of said shell, a tubular electrode within said sleeve and abutting against the insert at the insert end of said sleeve, an extension of the electrode supporting said 10 electrode in position and extending outwardly centrally of said insert, compression seals of yielding material for sealing the ceramic radially within the open end of said shell and sealing said electrode with respect to said shell, a body of 15 mercury in said shell and adapted to make and break contact between said electrode and shell over the extending edge of said sleeve member, and an anhydrous alkaline liquid fill in said shell for dissipating heat from said edge to all 20 parts of said shell.

2. A switch of the metallic envelope type comprising a tubular cup-shaped metallic shell having an enlarged open end, a ceramic insert closing the open end of said shell, an annular rubber gasket compressed between the external annular surface of said insert and the exterior surface of the open end of said shell, an integral cylindrical sleeve extending longitudinally from said insert into said shell, an annular electrode 25 surface engaging the interior of said sleeve intermediate the ends thereof, a stud securing said electrode in said sleeve and extending outwardly through said insert, a rubber gasket about said stud and compressed against said insert, an integral flange on said insert surrounding said stud and extending axially outwardly beyond the end of said shell, and a body of mercury for bridging said shell and electrode about the inner 30 end of said sleeve upon tilting of said switch.

3. A switch of the metallic envelope type comprising a tubular cup-shaped metallic shell having an enlarged open end, a ceramic insert closing the open end of said shell, a rubber gasket compressed between the external annular surface of said insert and the inner surface of the open end of said shell, an integral sleeve extending longitudinally from said insert into said shell, an electrode within said sleeve extending to a point adjacent the open end thereof, a stud securing said electrode in said sleeve and extending outwardly through said insert, a rubber gasket about said stud and compressed radially against said insert, insulating flange means on said insert surrounding said stud axially outwardly of the end of said shell, a body of mercury for bridging said shell and electrode, and means for making and breaking contact between said shell and electrode over the open end of 60 said sleeve.

4. A mercury switch of the closed metallic envelope type comprising a liquid fill consisting of an anhydrous alkaline liquid of low vapor pressure and having a substantially constant viscosity within the temperature range to which it is subject and being inert with respect to the mercury in said switch, said liquid fill comprising approximately 3% of the volume of the switch envelope.

5. In a mercury switch having a switch envelope, an anhydrous alkaline liquid fill therein above the mercury in said envelope, the volume of said fill being such that complete vaporization thereof will not produce a pressure sufficient to 70

rupture said envelope and associated parts of said switch.

6. In a mercury switch, a metallic cup-shaped shell, a ceramic insert in the open end thereof, compressible gasket means between said shell and insert, an electrode carried on the inner surface of said insert and having an outwardly extending shank, gasket means about said shank and compressible against said insert, a body of mercury in said shell of such quantity that the meniscus height thereof is substantially equal to the radial distance between the inner surface of said shell and the peripheral surface of said electrode, and a vaporizing partial liquid fill in said shell for dissipating heat therein during rapid operation of said switch, said gasket means being so shaped as to relieve excessive internal pressures in said shell but preventing entrance of air thereinto.

20 7. A heavy duty switch comprising a metal shell, an insulator, and an electrode defining an envelope which consists chiefly in a metal heat conducting wall and which is of great strength to resist internal pressure, a body of substantially pure mercury adapted to make and to break contact between the metal shell and the electrode, and a thin film of a viscous anhydrous alkaline liquid of high boiling point which is in contact with the mercury and which is vaporized at the point of heat generation and condensed upon the metal walls of the envelope to dissipate heat and equalize the temperature of the parts of the switch, the amount of liquid in said envelope being so low that excessive pressure is avoided by vaporization of the liquid as fast as it flows to the point of heat generation.

8. In a mercury switch of the sealed envelope type having iron electrodes and a body of substantially pure mercury for making and breaking circuit between the electrodes, a limited fill of triethanolamine providing not substantially more than a thin film which is adapted to be vaporized locally by the action of making or breaking the circuit, the vapor thereof engaging the walls and there being condensed.

45 9. In a mercury switch, a tubular ferrous envelope, a plug of insulation closing said envelope, the end of said envelope being beaded over a portion of the plug to retain said plug against internal pressure, a central electrode extending through and sealed to said plug and having a head upon the inside thereof preventing the expulsion of the electrode by internal pressure, a body of substantially pure mercury in the envelope for connecting and disconnecting the shell and electrode, and a small quantity only of ethanolamine in said envelope and in contact with the mercury, said ethanolamine being present in less than 5% of the free internal volume of the envelope and being capable of being vaporized locally by operation of said switch under load in making and breaking the circuit.

10. In a mercury switch, a tubular ferrous envelope, a plug of insulation closing said envelope, the end of said envelope being beaded over a portion of the plug to retain said plug against internal pressure, a central electrode extending through and sealed to said plug and having a head upon the inside thereof preventing the expulsion of the electrode by internal pressure, a body of substantially pure mercury in the envelope for connecting and disconnecting the shell and electrode, and a small quantity of an anhydrous alkaline liquid of a boiling point in excess of that of water, said liquid forming a thin layer

of substantially not more than a film in contact with the mercury at the point of greatest heat generation, said film being locally vaporized and the vapor carrying the heat to the envelope to equalize the same.

5 11. In a heavy duty mercury switch of the metal envelope type comprising a metal shell and an insulated electrode sealed together and insulated from each other, a body of substantially pure mercury for making and breaking connection between the shell and the electrode, said shell being beaded over the insulation of the electrode to provide a closed envelope capable of withstanding high internal pressures and temperatures substantially in excess of boiling water, 10 and a small quantity of anhydrous triethanolamine forming a film of liquid in contact with the mercury and being vaporized locally by the heat of the current to transfer heat from the point of vaporization to cooler parts of the envelope, where it is condensed.

12. In a mercury switch, a metallic cup-shaped shell, an insert closing one end of said shell, a body of mercury in said shell, an electrode carried at the inner end of said insert and radially spaced from said shell a distance substantially equal to the meniscus height of said mercury, said insert having an annular recess in the radial inner face thereof about said electrode of a curvature corresponding to the curvature of the approaching edge of said mercury, and a shank on said electrode extending outwardly through said insert.

20 13. In a mercury switch, a ceramic cup-shaped envelope having an open end and having an enlarged annular wall portion about said end, an electrode sealed in the opposite end of said envelope, a second tubular sleeve electrode extending into the open end of said envelope and terminating within said envelope at a point 25 spaced from said electrode, a retaining flange for said second electrode embracing the enlarged wall portion of said envelope, and resilient sealing means compressed between said flange and said enlarged wall portion.

35 14. In combination, a pair of cup-shaped members disposed in telescoping relation with the open ends thereof in overlapped relation to form a switch envelope, annular sealing means surrounding an end of one of said members, means 40 carried by the other member for radially compressing said sealing means into sealing engagement to form a sealed switch chamber, a body of mercury in said chamber, one of said members being metallic and the other being formed of 45 refractory insulating material, and an electrode carried within said chamber by said insulating member and spaced from the other member, said mercury bridging between said electrode and said other member upon tilting of the switch chamber.

50 15. In combination, a cup-shaped ceramic member, a cup-shaped metallic member fitting into and extending toward the closed end of said ceramic member, electrode means carried within the closed end of said ceramic member, 55 an insulating ring within said ceramic member between said electrode means and the inner end of said metallic member forming an inclined raceway therebetween, and fluid conducting means for effecting connection between said 60 metallic member and said electrode means over said raceway upon tilting of said switch.

65 16. In combination, an elongated cup-shaped ceramic member having an open end, a tubular electrode sleeve sealed in the open end of said 70

member, electrode means carried within said member at the closed end thereof and spaced from the inner end of said electrode sleeve by an annular wall portion of said ceramic member, and a body of mercury in contact with said electrode sleeve and movable into contact with said electrode means upon tilting of said ceramic member.

17. In a metallic envelope mercury switch having two bodies of mercury adapted to make and break contact over an insulating surface by relative movement therebetween, a film of an anhydrous alkaline liquid over said bodies of mercury, said film serving to maintain maximum surface tension of said mercury and to assist its movement, the films on said bodies of mercury being compressed therebetween upon relative movement toward each other to increase the head of mercury at the contacting surfaces, and the potential across said bodies of mercury puncturing said film to produce instantaneous enlarged surface contact between said bodies for reducing the resistance to passage of current through said contacting surfaces.

25. 18. In a mercury switch, a cup-shaped metallic envelope having an enlarged open end, a ceramic insert in said open end having an external annular shoulder, resilient sealing means between said enlarged end of said envelope and said shoulder, said enlarged end having its defining edge pressed radially inwardly axially outwardly of said shoulder to lock said insert in sealed position therein, said insert having a tubular sleeve extending axially into said envelope in spaced relation thereto, a tubular electrode within said sleeve terminating adjacent the inner end thereof and having a shank portion extending outwardly through said insert, and a body of mercury in said envelope for bridging between said electrode and envelope and making and breaking contact over the defining edge of said sleeve.

19. Means for dissipating heat from the point of generation thereof in a sealed metallic envelope mercury switch having a ceramic insert in one end thereof carrying an electrode and having a body of mercury therein adapted to make and break contact between said envelope and electrode over an internal surface of said insert, comprising an anhydrous alkaline liquid fill of small volume compared to the internal volume of said switch and adapted to adhere to the mercury, said fill having a relatively high boiling point whereby upon arcing at said surface said fill vaporizes and passes to cooler portions of said switch where it is condensed and flows by gravity back to the point of heat generation.

20. Means for dissipating heat from the point of generation thereof in a sealed metallic envelope mercury switch having a ceramic insert in one end thereof carrying an electrode and having a body of mercury therein adapted to make and break contact between said envelope and electrode over an internal surface of said insert, comprising an anhydrous alkaline liquid fill of small volume compared to the internal volume of said switch and adapted to adhere to the mercury, said fill having a relatively high boiling point whereby upon arcing at said surface said fill vaporizes and passes to cooler portions of said switch where it is condensed and flows by gravity back to the point of heat generation, said vaporization producing an increased pressure in said switch tending to minimize arcing during making and breaking of contact.

21. In a mercury switch of the heavy duty

type, a cup-shaped metal shell forming one electrode and having an enlarged open end, a refractory insert in said open end having an axially tapered bore opening into the interior of said envelope, an annular resilient gasket interposed between the external annular surface of said insert and the adjacent internal surface of the enlarged end of said shell, said shell having its defining edge forced radially inwardly to effect radial and axial compression of said gasket, an electrode carried within said bore and having its periphery spaced from the annular defining surface of the small end of said bore, a body of mercury retained in said bore in contact with a portion of the face and periphery of said electrode, and a second body of mercury in said shell adapted to make and break contact with said first body of mercury at a point spaced from said electrode.

22. In a metallic envelope mercury switch having a substantially cup-shaped switch chamber defined by metallic walls and closed at one end by a refractory ceramic insulator carrying a metallic electrode, said chamber having a liquid contactor movable upon tilting of said switch to make and break contact between said envelope and said electrode, the method of maintaining the switch cool during operation at its rated capacity which comprises providing a limited fill of an anhydrous alkaline liquid which clings to and moves with said contactor, and has a boiling point below the temperature to which flow of normal rated current tends to heat said conductor, vaporizing said liquid fill at the point of said contact between said envelope and said electrode by the heat generated in said contactor, providing unrestricted movement of said vapor into contact with said metallic walls to dissipate said heat therefrom and to condense said vapor, and providing for free return of said condensate into contact with said contactor.

23. A switch comprising a first cup-shaped member having a central axially projecting tubular portion secured to the base thereof and defining therewith an annular groove, a second cup-shaped member having its open end sealed in said groove, an electrode carried at the closed end of said second member, and fluid contacting means for bridging between said electrode and said tubular portion upon tilting of said switch.

24. A ceramic insert for a mercury switch comprising a cylindrical portion and an enlarged head portion having a tapered external surface converging toward the cylindrical portion, said insert having imperforate side walls and having a conical tapered runway terminating in a sharp peripheral edge defined by a radially extending groove terminating the conical runway.

25. In combination in a mercury switch, a bushing of refractory insulation having imperforate side walls and having a peripheral shoulder defining a wall of a mercury retaining pocket and a bore extending in one direction from said shoulder and forming a runway for mercury, said bushing having a substantially cylindrical portion extending in the opposite direction from said shoulder to form a part of said mercury retaining pocket, a tubular metal shell having an enlarged sealing portion having spaced inwardly extending shoulders for holding the bushing against endwise displacement in either direction relative to the shell, and a resilient annular body of insulation disposed between the shell and said

bushing and being held in compression upon the external peripheral wall of the bushing whereby the bushing is also placed under compression.

26. The combination of claim 25 with an electrode carried by the bushing, said electrode having a disc-shaped portion closing off said cylindrical portion and forming a wall of said pocket and having a stem portion extending outside said

bushing, a resilient deformable sealing bushing surrounding said stem within said refractory bushing, and means for holding said sealing bushing in compression to seal the electrode to the refractory bushing.

CERTIFICATE OF CORRECTION.

Patent No. 2,132,920.

October 11, 1938.

PAUL S. BEAR, ET AL.

It is hereby certified that error appears in the printed specification of the above numbered patent requiring correction as follows: Page 6, second column, line 27, claim 2, for the word "exterior" read interior; and that the said Letters Patent should be read with this correction therein that the same may conform to the record of the case in the Patent Office.

Signed and sealed this 29th day of November, A. D. 1938.

Henry Van Arsdale

(Seal)

Acting Commissioner of Patents.
